(57) **CLAIM**

The ornamental design for a phone case, as shown and described.

DESCRIPTION

FIG. 1 is a front, right and bottom perspective view of a phone case, showing my new design;

FIG. 2 is a rear, right and bottom perspective view thereof;

FIG. 3 is a rear, left-side and bottom perspective view of the phone case with the front flap in an open state;

FIG. 4 is a front, right-side and top perspective view of the phone case with the front flap in an open state;

FIG. 5 is a front view thereof;

FIG. 6 is a rear view thereof;

FIG. 7 is a right-side view thereof;

FIG. 8 is a left-side view thereof;

FIG. 9 is a bottom plan view thereof; and,

FIG. 10 is a top plan view thereof.

The broken lines shown in the drawings illustrate portions of the phone case, that form no part of the claimed design.
